(Cl. D22—2)

To all whom it may concern:

Be it known that I, Purley Amos Crandell, a citizen of the United States, residing at Burnley, Lancashire, England, have invented a new, original, and ornamental Design for Combined Can Opener and Gripping Tool, of which the following is a specification, reference being had to the accompanying drawing, forming part thereof.

Fig. 1 is a front elevational view of the can opener, showing my new design;

Fig. 2 is a rear elevational view of the can opener;

Fig. 3 is a side elevational view; and

Fig. 4 is an end view.

I claim:

The ornamental design for a combined can opener and gripping tool, as shown.

PURLEY AMOS CRANDELL.
